(57) **CLAIM**

The ornamental design for a cleaning device, as shown and described.

DESCRIPTION

FIG. 1 is a perspective view of a cleaning device showing my new design;

FIG. 2 is a front view of the cleaning device of FIG. 1, the rear view being a mirror image thereof;

FIG. 3 is a top view of the cleaning device of FIG. 1;
FIG. 4 is a bottom view of the cleaning device of FIG. 1;
FIG. 5 is a left side view of the cleaning device of FIG. 1, the right side view being a minor image thereof;

FIG. 6 is a close-up view of the teeth member of the cleaning device referenced in FIG. 1, which is fully disclaimed; and,
FIG. 7 is a close-up view of the portion of the cleaning device referenced in FIG. 2.

The features shown in broken lines are for the purpose of illustrating portions of the cleaning device that form no part of the claimed design. The circular broken lines shown in FIGS. 1-2 and 6-7 indicate cutoff boundaries for the enlarged detailed portion views and form no part of the claimed design. The dash-dot lines shown in the figures define the bounds of the claimed design and form no part thereof. The "UPROOT CLEAN" portion forming no part of the claimed design disclosure is a registered trademark of Uproot Lint LLC.
